UNITED STATES PATENT OFFICE

119,276

DESIGN FOR A SHOE

Albert W. Lutz, Brockton, Mass., assignor to Geo.
E. Keith Company, Campello, Mass., a corporation of Massachusetts

Application October 21, 1939, Serial No. 87,794

Term of patent 3½ years

To all whom it may concern:

Be it known that I, Albert W. Lutz, a citizen of the United States, residing at Brockton, in the county of Plymouth and State of Massachusetts, have invented a new, original, and ornamental Design for a Shoe, of which the following is a specification, reference being had to the accompanying drawing, forming part thereof.

In the drawing:

Figure 1 is a side elevation of a shoe embodying my new design, both sides of the shoe having substantially the same appearance; and

Figure 2 is a perspective of the shoe of Figure 1. My invention is characterized by the design formed by the particular arrangement of both the lines of stitching and the perforations as shown.

I claim:

The ornamental design for a shoe substantially as shown and described.

ALBERT W. LUTZ.
